Specification for Design.

Patented Aug. 24, 1920.

Application filed April 6, 1920. Serial No. 371,778. Term of patent 14 years.

To all whom it may concern:

Be it known that I, MAURICE L. A. A. ALLARD, a subject of the King of Belgium, residing at Akron, in the county of Summit and State of Ohio, have invented a new, original, and ornamental Design for a Tire-Tread, of which the following is a specification, reference being had to the accompanying drawing, forming a part hereof.

In this drawing—

Figure 1 is a surface configuration; and Fig. 2 is a sectional view of a tire tread, showing my new design.

I claim:

The ornamental design for a tire tread as shown.

MAURICE L. A. A. ALLARD.
